UNITED STATES PATENT OFFICE.

IRA F. GILMORE, OF BLOOMINGTON, ILLINOIS.

WIRELESS PIANO.

SPECIFICATION forming part of Letters Patent No. 699,840, dated May 13, 1902.

Application filed June 25, 1901. Serial No. 65,983. (No model.)

To all whom it may concern:

Be it known that I, IRA F. GILMORE, a citizen of the United States, residing at Bloomington, in the county of McLean and State of Illinois, have invented a new and useful Wireless Piano, of which the following is a specification.

This invention relates to musical instruments; and the object is to present an instrument to be performed upon in the same manner as an ordinary piano and having the same general outward appearance, but differing therefrom in the variety of tones produced and in the soft, resonant, and prolonged character of the tones as opposed to the sharp and clearly-defined tones of a piano.

The present invention combines in a simple, thoroughly practical, durable, and readily-operable manner a music-box having combined therewith means to give, if desired, a mandolin effect to music produced, a xylophone and coil-bells tuned to accord with the reeds and with the xylophone and to produce sympathetic notes, thus to prolong and increase the volume of tone. The different musical instruments thus presented are so combined and arranged that any one may be played to the exclusion of the other or any two combined or all combined to play at one time, and in addition means is provided whereby to increase or diminish the volume of sound of the music-box as a whole or to increase the volume of the bass reeds thereof and diminish the volume of the treble reeds, or vice versa.

The musical instrument of the present invention is designed, in part, as an improvement upon a musical instrument for which I obtained Letters Patent dated May 5, 1891, No. 451,667, such improvement referring more particularly to the mechanism for operating the reeds. In the patent referred to I employ ratchet-wheels, one for each key, to operate the reeds, and associate with such key a pawl to actuate the ratchet-wheel. In the present invention I dispense with the ratchet-wheels and pawls and operate the reeds directly from the keys. Furthermore, in the patent referred to the reeds are of the ordinary comb type, and I have found in practice that these are objectionable, for the reason that if one of the reeds breaks the whole comb

is rendered useless. I obviate this objection in the present invention by making each of the reeds a separate structure and associating the whole with a sound-board in such manner as to be readily removable when desired.

As a matter of further and specific improvement I provide means for producing the muffled sound attending the use of the ordinary soft pedal of the piano, the mufflers or dampeners to produce this effect to coact with the sound-board and with the sound-chamber in which the reeds of the music-box portion of the device are housed, the mufflers to be operated by one pedal and to soften the tones of the reeds and at the same time the tone produced by the vibration of the coil-bells that produce the sympathetic tones.

Further and more specific details of construction will hereinafter appear in the further presentation of the case.

In the accompanying drawings, forming a part of this specification, and in which like numerals of reference indicate corresponding parts, I have illustrated a form of embodiment of my invention capable of carrying my ideas into effect, it being understood that other forms of embodiment thereof may be employed without departing from the spirit of the invention, and in these drawings—

Figure 1 is a view in front elevation, partly in section. Fig. 2 is a view in vertical transverse section. Fig. 3 is an enlarged detail view, in sectional elevation, exhibiting certain mechanism not clearly shown in Fig. 1. Fig. 4 is a transverse sectional view, on an enlarged scale, taken on the line 4 4 of Fig. 2. Fig. 5 is a view in front elevation, partly in section, taken on the line 5 5, Fig. 3, and looking in the direction of the arrow thereon.

The piano-case (designated generally 1) comprises a suitably-constructed base 2, a front lower panel 3, a keyboard-support 4, a key-cover 5, hinged front piece 6, sound-opening front 7, suitably hinged to a cross-timber 8, extending from end to end of the casing, top 9, and ends 10. All of these parts may be of the ordinary or any preferred construction, and therefore require no specific description.

Arranged in the back part of the casing is a sectional sound-box 11, the same extending from a point near the base of the piano to a

point near the top thereof and nearly from end to end and supported for rocking movement in the case by a scale-pivot comprising a knife member 12, secured to the underside 5 of the sound-box, and a base 13, provided with a groove, in which the knife-pivot bears. Secured to the sound-box by bolts 14 is the sound-board 15, carrying a plurality of sound-board ribs 16, suitably spaced apart in horizontal relation to each other on the sound-board, the bolts 14 in this instance being arranged at the upper and lower portion of the sound-box and passing from the front thereof through the sound-board 15 and being held 10 in place by nuts 17, bearing against the back of the sound-board, the sound-board 15 at the part where the bolts 14 pass being provided with a rib 18, presenting a strengthening means for holding the bolts 14 in place. Between 15 the rib 18 and the lower portion of the sound-board and the rear edge of the bottom of the sound-box, at the upper and lower portions thereof, is inserted a muffling material, such as strips of felt 19, that operates in a readily-understood manner to prevent any rattling or clattering noise due to vibration of the sound-box and the sound-board. Upon the inner side 20 of the sound-board are arranged a plurality of coil-bells 20, one for each key, graded in size and tuned to accord with the reeds herein-after described, the bells being sympathetic in character, thereby to prolong and increase 25 the volume of sound of the instrument when played. The means herein shown of associating the coil-bells with the sound-board is one that may be employed and will be found thoroughly effective in use, and consists of a collar 21, through which passes a bolt 22 from the rear of the sounding-board and carrying 30 a nut 23 to clamp the bell firmly against the collar. By this arrangement the sound from the coil-bells will be transmitted to the sound-board and thence to a curved metallic sound-conductor 24, secured near the upper portion 35 of the sound-board and deflected upward and forward and terminating near the sound-opening front and operating to deflect the sound-waves toward the front of the instrument, whence they escape in the usual manner. It 40 is to be understood that the sound-opening front 7 may be the usual open-work structure, covered with any suitable textile fabric to preclude entrance of dust to the interior of the device, and is to be moved to and from 45 the sound-conductor 24, according as the sound is to be increased or diminished, as will be readily understood. The means for assembling the sound-conductor 24 with the sound-board 15 is in this instance by means 50 of bolts 25, of which any number may be employed, as may be found necessary. In order to permit the sound-conductor 24 to be disposed in the manner described, the front wall of the sound-box 11 is cut away, as shown 55 at 26, and through this cut-away portion the sound-conductor projects, as clearly shown in Fig. 1, the cut-away portion 26 being ex-

tended to a point some distance below the lower edge of the sound-conductor, thereby to obviate the presentation of any obstruction to the perfect transmission and escape 70 of sound.

Secured to the ends of the sound-box sections, as by bolts 27, is a sectional metallic sound-board 28, upon which is a bridge 29, 75 having its upper surface provided with as many transverse grooves 30 as there are keys on the instrument, and in these grooves are secured the reeds 31, each reed being a separate structure, whereby it may be removed 80 at will and replaced with a new one in case of injury. The reeds are held upon the bridge by a bridge-plate 32, clamped to the bridge 29 by bolts 33 and 34, of which there may be any number. The sound-board 28 is 85 connected with the sound-board 15 by sounding-posts 35, of which there may be any preferred number, and by this arrangement the sound will be conducted from the reeds 31 through the sounding-posts 35 to the sound-board 90 15, thence to the coil-bells 20, thence to the sound-conductor 24 and out through the sound-opening. It is to be understood that all 95 of these parts are to be rigidly assembled, so that there will be no jarring or buzzing sound, which would result from any loose assemblage 100 of the parts. Secured to the bridge-plate 32 by the bolts 34 are arms 36, and secured to the sound-board 28 are similar arms 37, there being any desired number of the arms 36 and 37, the 105 outer face of these arms being turned at right angles to their length, as shown at 38, and are bolted to the semicylindrical sound-chamber 39, in which the body of the reeds 31 are housed, an opening 40 being provided at the 110 front of the sound-chamber 39, through which the reeds project to be engaged by the picking mechanism presently to be described, as clearly shown in Fig. 1. The manner of assembling the sound-chamber 39 with the arms 115 36 and 37 is through the medium of bolts 41, these being passed through from the outside 120 of the chamber and into the portions 38 of the arms, as shown in Fig. 1. In order that the chamber 39 should have the highest 125 sound-conducting properties, the same is made of sheet metal of any desired thickness and has associated with it end plates 42, these plates being cut away at each end of the cylinder to permit the sound-board 28 to project beyond the same and to be secured to the 130 ends of the sound-box.

The sound-box 11 is made in two parts, designed to be independently adjustable and to carry with them the bass or treble reeds 31, 135 thereby to increase or diminish the volume of sound of the bass and treble reeds. To effect this adjustment, I provide two rods 43, the inner ends of which are threaded to engage with the respective fronts of the two 140 sections of the sound-box, each rod passing through supporting-timbers 44, secured to the ends of the casing, the openings through which the rods 43 pass being vertically elong-

gated to permit these rods to have a slight vertical movement to compensate for the arc described by the sound-box in being moved to and from the operative ends of the reeds.

5 The rods 43 carry each two collars 45, held thereon by bolts 46, these collars to bear against the opposed faces of the timbers 44, and thereby hold the sound-box in its adjusted position, whether it be vertical or 10 otherwise, the tendency of the sound-box, due to its association with the sound-board 15 and its attached mechanisms, being to tilt forward, and by the employment of the collars referred to this will be obviated. To 15 effect adjustment of the sections of the sound-box, and with them the sections of the semicylindrical sound-chamber and the bass and treble reeds, (it being understood, of course, that said chamber will be in two sections 20 corresponding with the sections of the sound-box,) the hand-wheels 47, carried by the rods 43, are turned to the right, and thus will move either the bass or treble reeds in greater overlapping relation with the pickers 25 to be described, a reverse movement of the hand-wheels moving the sound-box back to its normal or vertical position. By the employment of these two threaded rods 43 and the manner of associating them with the 30 sound-box fine gradations of sound may be produced, as by moving the bass-reeds to overlap the pickers as much as possible, and by moving the treble-reeds in the reverse direction to cause very slight overlapping of the 35 pickers loud tones will be produced on the bass-reeds and soft tones on the treble-reeds.

The reverse of the above results may be obtained by transposing the adjustment of the sections of the sound-box.

40 The means for picking the reeds 31 to produce a music-box effect comprises picker-arms 48, mounted for longitudinal movement in guides 49, secured to the ends of the key-bars 50, the latter being supported upon the 45 key-balance rail 51 in the usual manner. Each picker-arm comprises a piece of metal having a pointed end to engage with the point of the reed and is mounted in a longitudinal chamber in the guide 49, as clearly shown in Fig. 3.

50 In order to project the picker-arm into the path of the reed when a key is depressed, there is associated with each picker-arm a plate 52, the ends of which are reversely curved, as at 53 and 54, to present cam-sur- 55 faces to engage similar surfaces 55 and 56, formed on two supports 57 and 58, hinged, respectively, to a cross-timber 59, secured at its ends to the ends of the casing and to the upper inner edge of the front panel 3, as shown 60 at 60 and 61, respectively. The supports 57 and 58 are connected by a bar 62, secured to the support 58 by two bolts 63 and to the support 57 by a single bolt 64, and connected with the support 57 is a rod 65, working in 65 bearings formed in cross-timbers 66 and 67, secured to the ends of the casing, the rod 65 carrying a knob 68 at its outer end, by which

the rod may be turned. The inner end of the rod 65 engages a nut 69, secured within the support 57, the nut being held from turning 70 within the support by any suitable means. By turning the rods 65, say, to the right the supports 57 and 58 will be moved toward the front of the instrument, thereby moving the picker-arm 48 away from the end of the reed 75 and causing a slighter contact between the parts, thus to effect the playing of softer music, while a reverse movement of the rods will project the picker-arms and cause them to effect more violent vibration of the reeds. It 80 will be observed that when a key-bar is depressed and the inner end of the bar rises the cam-surface at the upper end of the plate 52, by contact with the cam-surface 56 of the support 57, throws the picker-arm backward 85 after the reed has been picked, thus leaving the picker-arm out of the path of the reed when the key-bar resumes its normal position, and when the key-bar drops, by reason of co-action between the cam-surface 54 of the plate 90 52 and the cam-surface 55 of the support 58, the picker-arm is again projected into the path of the reed. It is to be understood that all of the appurtenances here described in connection with the picker mechanism are to be 95 duplicated upon each key of the piano, so that a description of one will serve for all.

Mounted upon a cross-timber 70 is a shaft 71, carrying a plurality of arms 72, and the lower ends of these arms have secured to them 100 a sheet or strip of thin metal 73, curved at its lower end and adapted to rest upon the reeds 31 to produce a mandolin effect in the music. Secured to the shaft 71 in any suitable manner is an arm 74, having connected with it a 105 bar 75, which passes through the timbers 44 out to the front of the instrument and carries at its outer end a knob 76, by which the rod may be operated. By pushing the rod 75 inward the strip of metal 73 will be held free 110 from the reeds, and by pulling it outward the strip of metal will be brought into engagement with the reeds.

The xylophone comprises bars of metal 77, graduated in length to produce tones in consonance with those of the reeds, of which there will be one for each key. These bars are supported by suitable hangers 78 from the sound-board 79, supported upon the cross-beams 44 and 70, respectively, the sound-board being 120 associated with the beams by screws 80 in such manner as to cause the board to be thoroughly resilient. The sound-board carries a plurality of sound-board ribs 81, which operate in the well-known manner to increase 125 the vibratory qualities of the sound-board.

The bars under the operation of the keys are struck by hammers 82, these hammers being carried by curved resilient arms 83, mounted on a shaft 84, carried by the beam 130 67, the lower ends of the arms 83 being engaged by a block or projection 85, carried by the key-bars 50. When the arms are in the position shown in Fig. 3, upon depression of

the key-bar the hammer 82 will be impelled upward against a bar and will sound the note at the same time that the picker contacts with the reed corresponding to the key-bar depressed, thereby producing a double note—one sharp and clear in character and the other sonorous and resonant in character. In order to keep the arms 83 out of position to be engaged by the projections 85 of the key-bars, a sliding stop 86 is provided, this stop passing through the timber 44 and carrying on its inner end a depending arm 87, having its lower end connected with one end of a bar 88, which passes through the entire series of arms 83 and is supported at its other end by a hanger 87^a, as clearly shown in Fig. 1, the arm 87 being braced by a strut 89. When the stop 86 is pushed in, the bar 88 will contact with the under faces of the arms 83 and lift the entire series and hold them out of the path of travel of the projections 85, so that the instrument will produce only music-box tones, and when the stop is pulled out the arms 83 will be permitted to drop into the path of movement of the said projection, thereby to give a combined xylophone and music-box tone to the music.

As a means for operating the sound-opening front 7 I provide a pedal 90, fulcrumed in the usual manner upon a pedestal 91, the inner end of the pedal carrying a rod 92, the upper end of which is secured to the arm 93, projecting inward from the lower rearward portion of the sound-opening front. By this simple arrangement by depression of the pedal 90 the sound-opening front may be opened to permit escape of the largest volume of sound.

As a means for muffling the sound-chamber 39 and sound-board 15 I provide two muffling-boards 94 and 95, respectively, the muffling-board 94 being a flat surface to engage with the sound-board 15 and the muffling-board 95 being curved to conform to the contour of the sound-chamber 39. The operative faces of both of these muffling-boards carries a facing of felt 96 or other suitable material, which operates in a well-known manner to prevent vibration of the parts with which it contacts. To the muffler 94 is connected an arm 97, fulcrumed upon a pin 98 on the lower portion of the sound-box 11, the outer end of the arm 97 being connected with a rod 99, the upper end of which carries the muffler-board 95, the rod 99 carrying a padded stop 100, upon which the muffler 95 rests when not in use. The lower end of the rod 99 connects with the pedal 101, extending to the front of the instrument and contiguous to the pedal 90, the pedal 101 being also fulcrumed upon the pedestal 91. It will be readily understood that upon depression of the pedal 101 both the muffler-boards 94 and 95 will be brought into engagement with the sound-board 15 and sound-chamber 39 at the same time, so that by this simple arrange-

ment of mechanism the employment of an extra pedal is obviated.

From the foregoing description it is thought that the operation of the instrument will be readily understood; but in order that the advantages accruing from the arrangement of mechanism described may be more fully appreciated a description of the instrument either as a music-box, a combined music-box and xylophone, or a combined music-box having mandolin effect and xylophone will be given. When the device is to be used as a music-box pure and simple—that is to say, when only a music-box is desired—the stop 86 is pushed in to throw the xylophone-hammers out of the path of engagement of the projections 85 on the key-levers, and the stop 76 is pushed in to move the metallic plates 73 out of engagement with the reeds 31. Upon the keys being operated the reeds will be picked through the picking mechanism described, and the vibration of the reeds will be transmitted through the sound-board 28, thence to the sound-board 15 and coil-bells 20, thence to the metal sound-conductor 24, and thence out to the sound-opening, the same to be opened or closed, as may be desired. To modulate the tones of the volume of music, the pedals 99 and 101 may be operated to produce the desired effect.

When the instrument is to be operated as a music-box with mandolin effect, the stop 76 is pulled out to bring the metal plates 73 into engagement with the reeds, and when the instrument is to be operated as a combined xylophone and music-box the stop 86 is pulled out, thereby to allow the arms 83 to come into the path of movement of the projections 85 of the key-bars 50. As before pointed out, should it be desired to increase or diminish the volume of sound of the reeds the stops 47 will be moved out or in to produce the desired result.

It will be seen from the foregoing description that while the instrument presented will produce a variety of soft and pleasant tones the combination and arrangement of mechanism for producing these is of such simple character that liability to derangement in use or breakage is reduced to a minimum, and, further, that by reason of the arrangement set forth repairs may be readily effected.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

What I claim is—

1. In a wireless piano, the combination with a casing, of a laterally-movable sound-box therein, said box having a sounding-board

- constituting the rear wall thereof, of reeds having their rear ends located contiguous to the sounding-board and extended beyond the front of the box, a sound-chamber movable with the box, means for operating the reeds, and means extended beyond the casing for moving the box.
2. In a musical instrument, the combination with a sound-box having a sounding-board constituting the rear wall thereof, of a series of reeds having their rear ends located contiguous to the sounding-board, a sound-chamber partially inclosing the reeds and having an open side located within the sound-box, and reed-operating mechanism disposed to engage the front ends of the reeds.
3. In a wireless piano, the combination with a casing and a vertically-disposed and tiltably-mounted sound-box therein having a sounding-board constituting the rear wall of the box therein, of a series of reeds within the box and extended beyond the front wall thereof, reed-operating mechanism located in advance of the reeds, and means extended beyond the casing for tilting the sound-box to effect the endwise adjustment of the reeds.
4. In a musical instrument, the combination with a sound-box having a sounding-board constituting its rear wall, of a semicylindrical sound-chamber extended from the front wall of the sound-box and having an open side disposed adjacent to the sounding-board, a series of reeds partially inclosed by the sound-chamber, reed-operating mechanism disposed to engage the front ends of the reeds, and means for moving the sound-box for the purpose of moving the reeds toward or from their operating mechanism.
5. In a musical instrument, the combination with a vertically-disposed sound-box having a sounding-board constituting its rear wall, of a horizontally-disposed sounding-board located within the sound-box, reeds mounted on the horizontal sounding-board and extended through and beyond the front side of the box, a sound-chamber partially inclosing the reeds and means for operating the reeds.
6. In a musical instrument, the combination with a sound-box having a sounding-board constituting the rear wall thereof, of a horizontal sounding-board located within the box, reeds mounted on the horizontal sounding-board and extended beyond the front side of the sound-box, a rearwardly-opening sound-chamber partially inclosing the reeds and opening into the sound-box, and reed-operating mechanism.
7. In a musical instrument, the combination with a vertically-disposed sound-box, and a sounding-board constituting the rear wall thereof, of a horizontal sounding-board located within the box and disposed in close relation to the vertical sounding-board, a series of reeds carried by the horizontal sounding-board and extended beyond the front of the sound-box, a semicylindrical sound-chamber supported by the horizontal sounding-board and having its open rear side disposed adjacent to the vertical sounding-board, and reed-operating mechanism located in front of the semicylindrical sound-chamber.
8. In a wireless piano, the combination with a vertically-disposed, tiltingly-mounted sectional sound-box provided with a sounding-board constituting the rear wall thereof, of a series of reeds supported within the sound-box and terminating at one end adjacent to the sounding-board, reed-operating mechanism disposed to engage the front ends of the reeds, and means for tilting either section of the sound-box.
9. In a musical instrument, the combination with a sound-box and a sounding-board constituting the rear wall thereof, of a sound-conductor secured to the sounding-board and extended through the opposite wall of the box, a sound-chamber extended through the wall of the sound-box at a point below the sound-conductor and having its rear open side disposed adjacent to the sounding-board, a series of reeds partially inclosed by the sound-chamber, and means for operating the reeds.
10. In a musical instrument, the combination with a sound-box having a sounding-board constituting one wall thereof, of reeds mounted within the box and extended through the side thereof opposite the sounding-board, sympathetic sounding devices mounted on the sounding-board and within the box, and means for operating the reeds.
11. In a musical instrument, the combination with a sound-box, and a sounding-board constituting the rear wall thereof, of a series of reeds mounted within the box and extended from the sounding-board to a point in advance of the box, a semicylindrical sound-chamber partially inclosing the reeds and having a rear open side disposed contiguous to the sounding-board, and sympathetic sounding devices carried by the sounding-board within the box.
12. In a musical instrument, the combination with a sound-box, and a sounding-board constituting the rear wall thereof, of reeds extended laterally from the sounding-board, a semicylindrical sound-chamber partially inclosing the reeds and having an open side located adjacent to the sounding-board, a sound-conductor extending laterally from the sound-box at a point above the sound-chamber, and a series of sympathetic sounding devices mounted on the sounding-board within the box.
13. In a musical instrument, the combination with the reed-operating mechanism, of two separate series of reeds, and means for moving the series of reeds independently toward or from the reed-operating mechanism.
14. In a musical instrument, the combination with reed-operating mechanism, of reeds movable endwise toward or from the reed-operating mechanism, said reeds being divided

into independently-movable series, and means for moving each series of reeds independently of the other series.

15. In a musical instrument, the combination with a sound-box composed of independently-movable sections, of reed-operating mechanism in spaced relation to the box, and a series of reeds mounted upon and movable with each section of the sound-box.

16. In a musical instrument, the combination with a sound-box composed of a pair of vertically-disposed independently-movable sections, the rear wall of each section being formed by a sounding-board, a series of horizontal reeds extended from within each of the sound-box sections, reed-operating mechanism disposed to engage the ends of the reeds, and means for effecting the independent movement of the sections of the sound-box.

17. In a musical instrument, the combination with a series of keys, and a series of resonant bars suspended above the same, of pivoted hammers arranged to strike the bars and each disposed to be directly engaged by a key, a series of reeds disposed end to end with the keys, and pickers extended from the rear ends of the keys and disposed to engage the reeds.

18. In a musical instrument, the combination with a series of keys, of a sounding-board located above the same, a series of resonant bars suspended from the sounding-board, a series of pivoted hammers arranged for direct actuation by the keys, means for moving the hammers simultaneously into or out of operative relation with the keys, a series of reeds disposed end to end with the keys, and pickers extending from the ends of the keys to engage the reeds.

19. In a musical instrument, the combination with keys and reeds disposed end to end, of pickers extending from the rear ends of the keys and disposed to engage the reeds.

20. In a musical instrument, the combination with a key, and a reed disposed beyond the rear end thereof, of a picker slidably mounted in the key, and means for automatically moving the picker to cause it to engage the reed during one movement of the key and to clear the reed during the opposite movement thereof.

21. In a musical instrument, the combination with a key provided with a guide in its rear end, of a picker movably mounted in the guide, cams arranged to shift the picker longitudinally, and a reed disposed to be engaged by the picker during one movement of the key.

22. In a musical instrument, the combination with a key, a longitudinally-movable picker mounted in the rear end thereof, a cam-plate associated with the picker and extended above and below the same, reversely-curved guides disposed above and below the key for engagement with the cam-plate to shift the picker longitudinally in opposite directions during the opposite movements of the

key, and a reed disposed beyond the key for engagement with the picker.

23. In a musical instrument, the combination with a key, a picker and a reed, of a cam-plate carried by the picker, a movable support having a cam-face disposed for engagement with the cam-plate, and means for adjusting the position of the support.

24. In a musical instrument, the combination with a key provided with a picker in its rear end, and a reed arranged for engagement by the picker, of movable supports disposed above and below the key and having cam-faces, a cam-plate carried by the picker and disposed for engagement with the curved faces of the supports, and means for shifting the position of the supports.

25. In a musical instrument, the combination with a key, a picker operated thereby and a reed, of hinged supports located at opposite sides of the picker and provided with cam-faces, a cam-plate carried by the picker and having curved faces disposed for engagement with the cam-faces of the supports, means connecting the supports to insure their movement in unison, and an adjusting device connected with one of the supports to shift the position thereof.

26. In a musical instrument, the combination with the keys, pickers and reeds all disposed in substantially the same plane, of a series of metal strips terminally supported above the reeds and disposed for engagement with the free ends thereof, a series of resonant bars suspended above the keys, a series of pivoted hammers disposed below the resonant bars and having arms extended into engagement with the keys, means for moving the metal strips into and out of engagement with the reeds, and means for moving the several hammer-arms out of engagement with the keys.

27. In a musical instrument, the combination with a sound-box having a sounding-board constituting the rear wall thereof, of a sound-chamber extended through the front wall of the box, a series of reeds partially enclosed by the sound-chamber and extended into close relation to the sounding-board, and muffling devices for the sounding-board and sound-chamber, respectively.

28. In a musical instrument, the combination with a sound-box having a sounding-board constituting the rear wall thereof, of a sound-chamber extended through the front wall of the box, a series of reeds partially enclosed by the sound-chamber and extended into close relation to the sounding-board, muffling devices for the sounding-board and sound-chamber, respectively, and a single pedal connected to both of said muffling devices.

29. In a musical instrument, the combination with a casing having a movable sound-opening front and reeds, of a sound-box located within the casing and having a sounding-board constituting the rear wall thereof,

a curved sound-conductor extending from the sounding-board of the sound-box, through the front of the box and into close proximity to the sound-opening front, means for operating 5 the reeds, and means for adjusting the position of the sound-opening front to increase or diminish the sound.

30. In a musical instrument, the combination with a pivoted key, of a picker projecting 10 from the rear end thereof, and a reed secured at one end and having its free end inlapping relation with the picker.

31. In a musical instrument, a series of 15 reeds, a series of keys each carrying a picker-arm to engage a reed, and means for adjusting the picker-arm with relation to the reeds.

32. In a musical instrument, the combination with an adjustable sound-box carrying 20 reeds, of keys disposed in front of the sound-box, picker-arms adjustable on the keys and arranged to engage the reeds, means for adjusting the sound-box, and other means for 25 adjusting the picker-arms upon the keys, whereby the engagement of the arms with the reeds may be adjusted by the movement of both the reeds and arms.

33. In a musical instrument, the combination with an adjustable sound-box carrying a 30 series of reeds mounted therein, of a sound-conductor extending from the box, means located in the sound-box for producing sym- 35

thetic tones in consonance with those of the reeds, a semicylindrical sound-chamber partially inclosing the reeds, means for operating the reeds, and means for moving the 35 sound-box toward and from the reed-operating means.

34. In a musical instrument, the combination with a sound-box having a sounding-board constituting the rear wall thereof, of a 40 series of reeds having their rear ends located contiguous to the sounding-board, a sound-chamber partially inclosing the reeds, and reed-operating mechanism disposed to engage the front ends of the reeds. 45

35. In a musical instrument, the combination with a key, and a reed, of a picker extending from the rear end of the key for movement therewith and having limited independent movement, a cam for automatically effecting such independent movement of the picker when the key is depressed, and means for adjusting the position of the cam to regulate the extent of the engagement of the picker with the reed during the movement of the key. 50 55

In testimony that I claim the foregoing as my own I have hereto affixed my signature in the presence of two witnesses.

IRA F. GILMORE.
